COIN REGISTER

Murdock Macdonald, Cleveland Heights, Ohio

Application September 10, 1935, Serial No. 39,946

2 Claims. (Cl. 194—8)

The present invention relates to a device for registering and recording the deposit of metallic coins or tokens, and is particularly adapted for use in the collection of fares in railway and bus 5 operation.

The general object and nature of the invention is to insure the proper classification and registration of the coins collected, and at the same time to eliminate the erroneous acceptance and 10 registration of improper or incorrect sizes and values of coins.

Briefly outlined, the device embodying my invention consists of a plurality of coin receptacles, each of which is adapted to receive only a 15 particular size of coin, together with means for ejecting incorrect sizes of coins which might erroneously be deposited into the wrong receptacle. The device also includes means for signalling, recording and counting the deposit of only 20 the correct size of coins collected, as well as means for signalling the erroneous deposit of an incorrect size of coin. Additional objects and advantages of the invention shall become apparent as the following description proceeds.

To the accomplishment of the foregoing and related ends, said invention, then, consists of the means hereinafter fully described and particularly pointed out in the claims, the annexed drawing and the following description setting 25 forth in detail certain mechanism embodying the invention, such disclosed means constituting, however, but one of various mechanical forms in which the principle of the invention may be used.

In said annexed drawing:—

Fig. 1 is a view, partially in elevation and partially diagrammatic, illustrating the device embodying my invention, together with the wiring diagram of the signalling system attached thereto; Fig. 2 is a sectional view of one of the coin receiving units from the assembly shown in Fig. 1 and taken upon a plane normal to that of Fig. 1; Fig. 3 is a sectional view, similar to that of Fig. 2, but showing the operating parts in a 40 different position of movement; Fig. 4 is an enlarged detail view of the coin ejecting tongue and locking means; Fig. 5 is a top plan view of the unit shown in Fig. 2; and Fig. 6 is an enlarged 45 sectional view of the coin receiving passage and taken substantially along line 6—6 of Fig. 2.

Now referring more particularly to the drawing, the device includes a base plate 1 which may be suitably supported by means of vertical standards 2 and horizontal supporting bars 3. The

base plate 1 carries a plurality of upwardly extending coin receiving tubes 4, 41, 42 and 43. The inner diameter of each one of these tubes is substantially equal to the diameter of various sizes of coins with a slight clearance of course, in order that the coins will be able to pass through the tubes. Tube 4, for example, may have a diameter equal to that of pennies, tube 41 to that of nickels, tube 42 to that of dimes, and tube 43 to that of quarters. Also carried by the base plate 1 and extending transversely therefrom and parallel to the tube 4, there is another cylindrical tube 5 of lesser diameter. Each one of the units, as shown in Fig. 1 and as viewed therein from left to right, has the respective secondary tubes 51, 52 and 53 of lesser diameter.

At this point it should be noted that each one of the coin receiving units, as more fully illustrated in Figs. 2, 3 and 5, is of identical construction, but the coin receiving parts thereof are of different sizes. Hence corresponding reference numerals having the same first digits have been used in order to refer to similar parts of each of the units. The last digits of the reference numerals to corresponding parts for the three units to the right of the first one on the left bear the respective numerals 1, 2 and 3.

The upper ends of the tubes 4 and 5 terminate in and support a horizontally inclined plate 6. The plate 6 is composed of an insulating material such as fiber or bakelite and carries in its upper face two coin receiving channels or passages 7 and 8. As shown in Fig. 6, the passage 7 has a larger width, *a*, than the width, *b*, of the passage 8 located just below it. Adjacent the upper end of the coin receiving passage 7 and on either side thereof are located the metallic contacts 9 and 9'. Referring to Fig. 6, it will be noted that the contacts 9 and 9' do not extend to the side walls of the passage 8 but are insulated therefrom. Connecting wires 10 and 10' lead from the contacts 9 and 9', respectively. The wire 10 connects with a suitable electric power source, such as a battery 11, and the wire 10' connects with an electric signal light 14. Another connecting wire 13 leads from the signal light 14 to the wire 12 and thence to the battery 11. In this manner an electric circuit is formed from the contacts 9 and 9' through the battery 11 and to the signal light 14. As will be seen from Fig. 1, similar contacts are provided in the slots 71, 72 and 73 of each of the coin receiving units, and similar electrical connections and signal lights 141, 142 and 143 are provided

corresponding to each of the units. The signal lights 14, 141, 142 and 143 will each bear a different color, for example, red, yellow, green and blue, respectively. Such colors are denoted in Fig. 1 by the legends R, Y, G and B.

A bus wire 15 leads from the battery 11 to the connecting wires 101, 102 and 103 (corresponding to the wire 10) to each of the respective units.

The lower end of the tube 5 extends below the base plate 1 and is closed by a wall 17 of insulating material. An opening 18 adjacent the bottom of the tube 5 permits the withdrawal of a coin therefrom. The insulated bottom wall 17 carries a pair of spaced contacts 19 and 20, which are adapted to be bridged by a coin passing through and coming to rest on the bottom of tube 5. As will be seen from Fig. 1, a terminal wire 21 leads from one of the contacts in the tube bottom 17 to the battery 22. Another wire 23 leads from the other side of the battery 22 to the signal bell 24. The bus wire 25 leads from the other terminal of the signal bell 24 to the respective terminal wires 26, 261, 262 and 263, connected to the other contact on each one of the bottoms of the tubes 5, 51, 52 and 53. A second bus wire 27 connects the respective terminal wires 21, 211, 212 and 213 to the battery 22. In this manner the contacts in the bottom wall of each of the tubes 5, 51, 52 and 53 are electrically connected to the battery 22 and to the signal bell 24. A plate or tongue 30 is slidably mounted on the under side of the base 1 and is supported in such position by means of the fixed plate 31 which is suitably fastened to the base 1. The right-hand end of the tongue 30, as shown in Fig. 4, is concavely curved as at 32 into an arc whose radius of curvature is equal to that of the inner diameter of the tube 4. Adjacent the curved portion 32 are the two angularly inclined shoulders 33 and 34. The tongue 30 also has an elongated slot 35 whose width is equal to the inner diameter of the tube 5. The slot 35 leaves the interior of the tube 5 open at all times, regardless of the position of the tongue 30, in order that a coin entering such tube will be permitted to travel through it to the bottom. A pair of arms 36 and 37 are pivotally mounted as at 38 and 39, respectively, to the bottom supporting plate 31. The outer ends of the arms extend transversely towards each other and present the rectangular shoulders 41' and 42', as well as the angularly inclined or beveled faces 43' and 44'. The space between the arcuate portion 32 of the tongue 30 and the beveled faces 43' and 44' is of sufficient dimensions to accommodate the coin C which enters the tube 4 and drops to the bottom thereof. The tension spring 40 is connected to each of the arms 36 and 37 and tends to hold them in position against the sides of the tongue 30. A tension spring 45 is connected between the base 1 and the tongue 30 and tends to hold the latter in its left-hand position (with respect to Fig. 2).

The left-hand end of the tongue 30 extends upwardly through a slot 46 in the base 1 and is pivotally connected as at 47 to a link arm 48, which in turn is pivotally connected as at 49 to a second link arm 50. The link arm 50 is pivotally connected at 51' to the base 1. A small arm 52', rigidly carried by the link arm 50, is pivotally connected as at 53' to another link 54 which in turn is pivotally connected as at 55 to the lever 56 and large link arm 57. The lever 56 is fulcrumed as at 58 to the fixed bracket 59 mounted upon the base 1. The lever 56 is laterally offset, as at 60, in order to pass by the tubes 4 and 5 and has a manipulating button 65 on its outer end.

A short connecting arm 66 connects the large link arm 57 to the counter 67. A cover plate 68 extends over the top of the coin receiving passage plate 6 and has an upwardly flared portion 69 at its upper end for the purpose of guiding coins into the passages 7 and 8.

The operation of the device as above described is as follows:—

Assuming that a coin of the correct size is inserted in any one of the proper coin receiving channels or passages 7, 71, 72, or 73, it will first bridge the space between the contacts 9 and 9' and thereby complete the electric circuit between the battery 11 and any one of the signal lights 14, 141, 142 or 143, as the case may be, in which instance the operator, as well as any other observers, are apprized of the fact that the coin of a proper size and value has been inserted in the register. Likewise the size and value of the coin is also signalled, according to the color of the particular signal light whose circuit is closed by the insertion of the coin. The coin next proceeds down the passage 7 to the upper end of the tube 4, drops down the tube 4 to its bottom and to the position between the end of the tongue 30 and the ends of the arms 36 and 37, as shown in Fig. 4. The operator then moves the lever 56 by pressing down on the button 65. This movement of the lever 56 moves the several link arms 48, 50, 54, 57 and 66 to the position shown in Fig. 4. Upon such movement the tongue 30 is forced in a right-hand direction, and due to the camming action of the coin C against the beveled faces 43' and 44 of the arms 36 and 37, the coin is ejected from the bottom of the tube 4 into the hand of the operator.

In the event that a coin does not reach the tube 4 and thence to its bottom, or to the position as shown in Fig. 4, the points of the inclined portions 33 and 34 on the tongue 30 will bear against the shoulders 41' and 42' and thereby prevent further movement of the lever 56 and correspondingly of the link arms 57 and 66, which actuate the counter 67. In this manner the button 65 and lever 56 are locked against movement sufficient to register on the counter 67. Thus, it will be seen that it is necessary that a coin of the proper size reach the bottom of the tube 4 before the ejecting mechanism or the counting device can be actuated.

In the event that an improper size of coin, that is, a coin having a lesser diameter than the width of the channel 7 is inserted in any one of the coin receiving units, it will drop down into the lower coin receiving passage 8 and into the tube 5. An abutment member 70 is provided adjacent the lower wall of the tube 5 and in the channel 8, in order to prevent such an undersized coin from possibly bouncing or traveling past the upper end of the tube 5 and thence into the tube 4. When the undersized coin enters the tube 5, it drops down to the bottom thereof and bridges the contacts 19 and 20, whereupon the circuit between the battery 22 and signal bell 24 is closed, thus actuating and ringing the bell. In this manner the operator is informed of the fact that an improper size of coin has been inserted in any one of the respective coin receiving units. The operator then removes the improper size coin through the opening 18, thus again opening the circuit to the signal bell 24. The operator may then inspect the coin, which has been improperly inserted, and return it to the payer or refuse its acceptance if it is found to be spurious.

Other modes of applying the principle of my invention may be employed instead of the one

explained, change being made as regards the mechanism herein disclosed, provided the means stated by any of the following claims or the equivalent of such stated means be employed.

5 I therefore particularly point out and distinctly claim as my invention:—

1. In a coin register, the combination of a dual coin receiving passage of two different widths, the larger for the passage of correct size coins and the smaller for the passage of incorrect size coins, indicating means connected to the larger width passage for signalling the insertion of correct size coins in said dual passage, and a second indicating means located below and adapted 10 to receive coins from the smaller width passage for signalling the insertion of incorrect size coins in said dual passage.

2. In a coin register, the combination of a dual coin receiving passage of two different widths, the larger for the passage of correct size coins, and the smaller for the passage of incorrect size coins, indicating means connected to the larger width passage for signalling the insertion of correct size coins in said passage, a second indicating means located below and adapted to receive coins from the smaller width passage for signalling the insertion of incorrect size coins in said dual passage, and counting means located below said larger width passage and adapted to be rendered operative by coins therefrom for registering the number of only the correct size coins inserted in said dual passage.
